GAME BOARD

Thomas Briscoe, Coupeville, Wash.

Application November 26, 1945, Serial No. 630,842

1 Claim. (Cl. 273—134)

1

This invention relates to games as played upon a game board, and the primary object of the invention is to provide a novel form of game board provided with a centrally disposed turn table operable by a central knob, said turn table being differentiated diametrically in at least two colors and being surrounded by a stationary circular, up-standing rib, flange or fence for retaining a marble or marbles in place upon the turn table as same is rotated by the knob, there being formed outwardly of the said circular rib, flange or fence and upon the outer margins of the board several concentric, differently colored bands or circles, some of which correspond in coloring to the coloring of the segments of the turn table, said outwardly disposed and colored bands and circles being equally divided into sections by radial lines extended out from the circular rib, flange or fence, and there being lines of peg holes formed into said outer portions of the board in straight lines mid-way of the several sections, these holes being adapted to receive and removably hold play pegs as disposed therein by the players in the progress of the game, and in accordance with the rules adopted for such play.

Another object of the invention, and as here more particularly shown and detailed, is to provide a game board having centrally mounted thereon a circular and rotatable turn table with means for rotating same, said board being colorably differentiated on its upper face into two equal sections or semi-circular segments, a stationary, circular and up-standing rib, flange or fence surrounding the turn-table and adapted for retaining a marble thereon as the turn-table is rotated, and three differently colored rings or bands formed upon the board outwardly of the said rib, flange or fence, the central ring being relatively narrow and designated as a starting ring, the inner and outer rings being substantially wider than the central starting ring, said rings being radially and equally divided by radial section lines and there being straight and radially extended rows of peg holes formed in the board mid-way between the said circular rib, flange or fence, outwardly through the three differently colored rings, the inner and outer rings corresponding in color to the colors of the semi-circular segments of the turn-table, and the peg holes being adapted to removably receive and hold play pegs as disposed therein by the players under the rules of the game.

With the stated object in view, together with such other and additional objects as may appear from the specification, attention is directed to the

2

drawing, constituting a part of this specification, and wherein

Figure 1 is a plan view of the game board as constructed and laid out in accordance with this invention, there being a marble shown as positioned upon the turn-table thereof, as required in the play of the game. Figure 2 is a diametrical section on the line 2—2 of Figure 1, there being a play peg indicated in dotted lines as positioned in one of the peg holes of the board. Figure 3 is a detail of one of the play pegs as used in the play of the game.

In practising this invention I provide a suitably flat and rectangular game board, represented generally at 5, and preferably square. A pivot pin 6 is rigidly seated centrally in the upper side of this board, and a turn-table 7 of disc-like formation is bored into centrally and perpendicularly at its under side to form a pin receiving socket 8 adapted to freely and rotatably receive the pivot pin 6, whereby the turn-table is operatively mounted in place, and may be rotated as desired by means of the central up-standing knob 1a. It is to be noted that the central portion of the turn-table 7 is convexed upwardly while the peripheral margin thereof is flat as shown at 7b, thus providing a suitable run-way for the marble 9 as used in the play of the game, as later to be explained.

30 A circular rib, flange or fence-strip 10 is fixedly mounted upon the board 5, immediately surrounding the turn-table 7 and concentric therewith, being spaced slightly from the margins thereof so that it may rotate freely therein, this 35 rib, flange or fence being raised substantially above the upper peripheral margin 7b of the turn-table, for retaining the marble 9 thereon in the course of the play. The upper surface of the turn-table 7 is equally and diametrically divided 40 into semi-circular sections 7c and 7d, these sections being colorably differentiated in red and black as here shown. As here shown outwardly of the flange or fence 10, there are depicted upon the board 5, three circular bands or rings 11, 12 45 and 13, all concentric with the pivot pin 6, the central ring or band 12 being relatively narrow and here shown as white in color, and for the purposes of description being designated as the "starting ring or band." On the other hand the inner and outer rings or bands 11 and 13 are respectively red and black in color, thus corresponding in color with the two semi-circular segments of the turn-table 7. These outer rings or bands 11, 12 and 13 are radially and equally divided by the equi-spaced, radial section lines 14,

whereby play-spaces 15 are provided for the several players involved in the game. Here eight such divisions and play-spaces are shown, but obviously the same may be increased or decreased as desired. Straight rows of peg holes 16 are formed in the board 5, the same being radially extended from the flange or fence 10 outwardly across the rings or bands 11, 12 and 13, mid-way between the section lines 14. The peg-holes 16 are designed and adapted to removably receive 10 and hold complementally formed play pegs 17 (Fig. 3). As here shown there is one such peg hole located medially within each of the play spaces 15 of the central ring 12, and two peg-holes medially within the play spaces of the inner and outer rings 11 and 13 respectively.

In the play of the game with the particular outfit as here shown and described, any desirable rules and system of play may be employed as may be agreed upon. The described outfit will accommodate eight players, and as an example of method of play each player would be given one of the play pegs 17 which he would position within the peg hole 16 of the starting ring 12, within his particular play space 15 of the board 5. With the marble 9 properly located upon the turn table 7, each player in turn and moving from left to right or vice versa as desired, then rotates the turn table 7 by means of the knob 18. This operation results in the marble 9 spinning around the peripheral margin 16 of the turn table and finally coming to rest upon either the red or black segment, 7c or 7d, of the turn table and in alignment with the play space 15 of one of the players. If the marble stops on the red segment of the turn table at the player's space, he then moves his play peg 17 from the starting line 12 into the first peg hole 16 in the red ring 11. If on the other hand the marble stops on the black segment, opposite the player's space, the player then moves his play peg 17 into the first or adjacent hole in the outer black ring 13. The next player to right or left then spins the turn table in similar manner, and scores his points on the board in the same way. Thus the players proceed in turn around the board, and until one of the players succeeds in locating his play peg into the second or outer peg hole of the outer

5 black ring 13, thus winning the game. Obviously any other desired mode and rules of play may be adopted, and likewise the particular structural features and arrangements of the board may be modified as may be desired in minor details and within the scope of the claim.

What I claim to be new and patentable is:

In a game device of the kind described, a flat game board having a circular turn-table pivoted at the center of the board, said turn-table being segmentally colored in diametrically divided halves to form semi-circular sections extending to the margins thereof, an upstanding circular flange on the board and surrounding the turn-table, there being three concentric rings depicted upon the game board outwardly of the said upstanding flange, the central ring being designated as a starting ring and being relatively narrow, the inner and outer rings being colored 15 to correspond with the coloring of the two segments of the turn-table and differing from the color of the central starting ring, these said three rings being all equally divided by equi-spaced radial section lines for providing play spaces therein between, and there being straight rows 20 of peg holes formed in the board and radially extended from the said circular flange outwardly across the said rings mid-way between the section lines, one of the peg-holes being located on the central starting ring within each of the several play spaces of the board, and two peg-holes within each play space of the inner and outer rings.

THOMAS BRISCOE.
